BASKET

Theophilus L. James, Dayton, Tenn., assignor to
Dayton Veneer & Lumber Mills, Dayton,
Tenn., a corporation of Tennessee

Application December 13, 1932
Serial No. 647,031

8 Claims. (Cl. 217—123)

This invention relates to baskets, particularly stave baskets, and embodies modifications of the invention disclosed in a co-pending application of Oliver M. James, for patent for Baskets, filed December 28, 1931, Serial No. 583,537, patented January 10, 1933, No. 1,894,236.

Baskets of the type to which this invention particularly relates are usually made on machines of the receptacle and plunger type by which a web of stave members is pressed to basket form, sufficient clearance being left between the interior of the receptacle and exterior of the plunger, when the plunger is forced into the receptacle, to accommodate a web of a certain thickness. Such webs are customarily formed of twenty stave members arranged in four series of five stave members each, the stave members of each series being arranged in radiated superposed relation, and the several series superposed one upon another with the stave members so relatively arranged as to span the spaces between stave members of adjacent series, so that when formed to basket shape the sides and bottom of the basket will be of what is known as closed form, that is to say, without gaps or spaces between stave members.

The ordinary stave basket, formed substantially as just described is not suitable for what is known as export trade, because the bottom and sides, but particularly the bottom thereof, are not sufficiently strong to stand the handling to which they may be subjected, and one object of this invention is to provide such a reinforcement for a stave basket of the type described that it will satisfy the requirements for baskets of the export type.

Another object of the invention is to provide a reinforcement for stave baskets having such characteristics and so entering into the construction or arrangement of the members forming the basket web that the web including the reinforcement may be formed to basket shape upon existing machines of the type referred to.

The invention comprises a stave basket the web of which is formed of a plurality of series of stave members arranged in radiated superposed relation, one of said series forming the reinforcing element and comprising stave members shorter than those of the other series and arranged in pairs with their ends overlapping so that each pair presents an end of single stave thickness for incorporation in the basket beneath the top hoop thereof, all as will be explained more fully hereinafter and finally claimed.

In the accompanying drawings illustrating the

invention, in the several figures of which like parts are similarly designated, Figure 1 is a perspective view of a basket constructed in accordance with and embodying the features of the present invention, the view being taken looking partly at the bottom of the basket. Fig. 2 is a perspective view similar to Fig. 1 but looking into the basket through the top opening thereof. Fig. 3 illustrates, on a reduced scale, the first series of stave members forming a part of the basket web. Fig. 4 is a view similar to Fig. 3 but showing the first and second series of stave members in proper relative arrangement. Fig. 5 is a view similar to Figs. 3 and 4 but showing the first, second and third series of stave members in proper relative arrangement. Fig. 6 is a view similar to Figs. 3, 4 and 5 but showing the first, second, third and fourth series of stave members in proper relative arrangement and secured together, and Fig. 7 is a perspective view showing one of the pairs of stave members which go to make up the third series of stave members which provide the reinforcement for the basket.

Referring particularly to Figs. 3 to 7 inclusive, as heretofore stated, the basket web comprises a plurality of stave members arranged in radiated superposed relation and preferably divided into four separate series, each series comprising in effect, five stave members which extend continuously across the bottom and up the sides of the basket. As shown in Fig. 3, the first series of stave members *a* is laid in the relationship shown, and then, as illustrated in Fig. 4, the second series of stave members *b* is laid over the first series with the members *b* comprising the second series arranged to substantially bisect the angles by which the stave members *a* of the first series are spaced, and then, as illustrated in Fig. 5, the third series comprising the stave members *c* and *c'*, which are of a length shorter than the members of the other series and are arranged in pairs with their ends overlapping, particularly as illustrated in Fig. 7, are laid over the stave members of the first and second series in such relation as to substantially bisect the angles forming the spaces between certain of the stave members of the first and second series and then, the final or fourth series of stave members *d* is laid over the first, second and third series in such relation thereto as to bisect the remaining angles forming the spaces between others of the stave members of the first and second series, and the stave members of all of the series are then fastened together at their intersection by nails or

other suitable fastenings *e* driven through them and appropriately clinched.

The web thus formed is pressed to basket shape and the bottom hoop *f*, top hoops *g* and *h* and 5 intermediate hoop *i* are applied and stapled or otherwise suitably fixed, as shown.

Although the series of stave members *c*, *c'*, might be either the first, second, third or fourth 10 series in the basket web, I prefer to so position it in the web that it becomes the third series therein. By thus positioning it, the first and second series will form a relatively smooth interior for the basket unbroken by the ends of the 15 stave members *c* and *c'* and the fourth series of stave members will form the exterior of the basket, supplemented by the staves *c* and *c'* which span the spaces between some of the staves *d* of the fourth series, and will serve to support and strengthen the bend where the bottom and sides 20 of the basket merge.

Baskets thus formed will have a reinforcement furnished by the series of stave members *c*, *c'* which spans the basket bottom and extends up its sides, preferably to a point beneath and capable of engagement by the top hoops *g* and *h* and 25 a portion of which terminates short of the top hoop and is engaged beneath the intermediate hoop *i* arranged adjacent to the midportion of the basket sides.

30 A basket thus formed has a bottom and sides of a strength and rigidity far superior to the similar parts of stave baskets as ordinarily constructed and, moreover, the extra reinforcement of the sides, particularly between the intermediate 35 hoop *i* at the midportion thereof and the bottom hoop *f* gives extra strength to this portion of the sides and prevents buckling or bulging when the baskets are stacked in large numbers, whether empty or filled.

40 Furthermore, due to the pairing of the stave members *c*, *c'* with their ends overlapping, as described, there is no more thickness in the web at its circumferential edge than is in a web of a similar form as ordinarily laid, and hence basket 45 forming machines of known types will handle the web of this improved reinforced basket as well as they will a basket web of the ordinary type.

It will be seen, by inspection of Figs. 5 and 6 50 that the paired stave members *c*, *c'* are staggered end for end in the series which they form, so that alternate stave members have their short ends appearing on the inside and outside of the basket. Although this is desirable, it is not es- 55 sential, and these paired stave members may be arranged thus, as shown, or this arrangement may be disregarded without in any way detracting from the strength of the basket, although perhaps sacrificing, to a certain extent, its sym- 60 metry of appearance.

It is to be noted that the paired stave members *c*, *c'* of the reinforcing series, arranged with their ends overlapped, form reinforcing elements which are of a length equal to that of the stave mem- 65 bers *a*, *b* and *d* of the other series, even though the length of the members *c*, *c'*, separately con- sidered, is shorter. Thus, in addition to provid- 70 ing reinforcing elements the outer ends of which are of single thickness a considerable saving in veneer stock is made.

I have shown and described the stave members *c* and *c'* as of such length that their short ends 75 extend to that point in the basket sides at which they will be engaged beneath the intermediate or midportion hoop *i* but, if desired, these stave

members could be of such a length that their short ends would project only to an extent up the sides to ensure their being engaged beneath the bottom hoop *f*.

It is to be noted that the added, interposed 80 material which forms the reinforcement, produces additional upset or inward bulge in the bottom of the basket, thus providing, in effect, an arched bottom which results in the load or weight of the basket contents being supported against the bot- 85 tom hoop.

Various changes and modifications are con- sidered to be within the spirit of the invention and the scope of the following claims.

What I claim is:—

1. A stave basket, comprising a basket web in- 90 cluding a plurality of series of stave members, one of said series comprising stave members shorter than those of the other series and arranged in pairs and so overlapped as to equal in length the stave members of the other series.

2. A stave basket, comprising a basket web in- 95 cluding outer and inner series of stave members and an intermediate series of stave members interposed between the outer and inner series and comprising a plurality of stave members shorter than those of the outer and inner series and ar- 100 ranged in pairs and so overlapped as to equal in length the stave members of the outer and inner series.

3. A stave basket, comprising a basket web in- 105 cluding a plurality of series of stave members ar- ranged in such relation as to provide the bot- 110 tom and sides of the basket, hoops applied to and encompassing the sides of the basket and ar- ranged adjacent to the top and bottom and midportion thereof, the stave members of one of said series being shorter than those of the other series and so paired in overlapping relation 115 as to equal the length of the stave members of the other series.

4. A stave basket, comprising a basket web in- 120 cluding a plurality of series of stave members ar- ranged in such relation as to provide the bot- 125 tom and sides of the basket, hoops applied to and encompassing the sides of the basket and ar- ranged adjacent to the top and bottom and midportion thereof, the stave members of one of said series being shorter than those of the other series and so paired in overlapping relation 130 as to equal the length of the stave members of the other series, one end of each of the stave members of the paired series being engaged be- 135 neath the top hoop and its other end terminating in the basket side short of said top hoop.

5. A stave basket, comprising a basket web in- 140 cluding a plurality of series of stave members ar- ranged in such relation as to provide the bot- 145 tom and sides of the basket, hoops applied to and encompassing the sides of the basket and ar- ranged adjacent to the top and bottom and midportion thereof, the stave members of one of said series being shorter than those of the other series and so paired in overlapping relation 150 as to equal the length of the stave members of the other series, one end of each of the stave members of the paired series being engaged be- neath the top hoop and its other end terminating in the basket side short of said top hoop but engaged beneath said bottom hoop.

6. A stave basket, comprising a basket web in- 155 cluding a plurality of series of stave members ar- ranged in such relation as to provide the bot- 160 tom and sides of the basket, hoops applied to and encompassing the sides of the basket and

arranged adjacent to the top and bottom and midportion thereof, the stave members of one of said series being shorter than those of the other series and so paired in overlapping relation

5 as to equal the length of the stave members of the other series, one end of each of the stave members of the paired series being engaged beneath the top hoop and its other end terminating in the basket side short of said top hoop but 80
10 engaged beneath said bottom hoop and the hoop encompassing the midportion.

7. In a stave basket, having a bottom and sides, and hoops encompassing the sides adjacent to the top and bottom and midportion thereof, a 85
15 reinforcing element comprising a plurality of stave members disposed in pairs and having their ends in overlapping arrangement, said reinforcing element assembled in the bottom and sides

of the basket and having one end of each of its stave members engaged beneath the top hoop and the other end of each stave member terminating short of said top hoop but engaged beneath another hoop.

8. In a stave basket, having a bottom and sides, and hoops encompassing the sides adjacent to the top and bottom and midportion thereof, a reinforcing element comprising a plurality of stave members disposed in pairs and having their ends in overlapping arrangement, said reinforcing element assembled in the bottom and sides of the basket and having one end of each of its stave members engaged beneath the top hoop and the other end of each stave member terminating short of said top hoop but engaged beneath the hoop of the midportion. 90
